UNITED STATES PATENT OFFICE.

JOHN H. PATTERSON, OF DAYTON, OHIO, ASSIGNOR TO THE NATIONAL CASH REGISTER COMPANY, OF SAME PLACE.

CASH INDICATOR AND REGISTER.

SPECIFICATION forming part of Letters Patent No. 414,442, dated November 5, 1889.

Application filed May 7, 1889. Serial No. 309,873. (No model.)

To all whom it may concern:

Be it known that I, JOHN H. PATTERSON, a citizen of the United States, residing at Dayton, in the county of Montgomery and State 5 of Ohio, have invented certain new and useful Improvements in Cash Registers and Indicators, of which the following is a full, clear, and exact description, reference being had to the accompanying drawings, forming part 10 of this specification.

My invention relates to that class of cash registers and indicators which are inclosed in a case or cabinet having a drawer-compartment containing a money-drawer or 'till', 15 which is held in its closed position by a locking device arranged to be released upon the operation of any key to permit the drawer to be partially propelled from its compartment; and it consists in a novel method of 20 arranging and supporting the drawer in said compartment, whereby when the locking device is released by the operation of a key the drawer will be automatically thrown forward and partially propelled from its compartment. 25 Its novelty will be herein set forth and specifically pointed out in the claims.

In the accompanying drawings, Figure 1 represents a sectional side elevation of a well-known form of machine with my improvements applied thereto. Fig. 2 represents a 30 sectional side elevation of the drawer-compartment, showing the drawer open. Fig. 3 represents a sectional side elevation of the drawer-compartment, showing a modified arrangement of the drawer and its supporting links.

The same letters of reference are used to indicate identical parts in all the figures.

Inasmuch as the general construction of 40 the machine I have illustrated is well known and is shown and described in a large number of patents, it will be sufficient here to say that A is the usual case or cabinet inclosing the registering and indicating mechanisms, 45 through the front portion of which case the front ends of the operating-keys B project, and in the upper rear portion of which is a glass-covered reading-opening C for the exposure of the indicating-tablets.

50 The registering and indicating mechanisms

are supported in a frame-work D, the keys B being pivoted on a shaft E, and carrying on their rear ends the vertically-guided tablet-rod F, having at their upper ends the figured indicating-tablets G, and provided with 55 shoulders a, arranged to be engaged by the supporting-wing H, actuated by the operation of the keys through the medium of the vibrating bar I, bell-crank J, tripping-dog K, and wing-extension L, in the usual manner. 60

M is the gong, sounded at the operation of each key by the hammer N, secured to the wing-extension L.

O O' are the registering-wheels, those of the lower bank being turned by the dogs b, 65 pivoted to the keys B, and each wheel of the upper bank being turned one number at each complete revolution of the corresponding wheel in the lower bank, in the usual manner.

In the lower part of the case is the usual 70 drawer-compartment P for the reception of the money-drawer, and into the upper rear portion of which projects the usual locking-bolt Q, suitably guided and carried on the end of a pivoted lever R, extending across the 75 rear side of the machine and arranged to be actuated to lift the bolt Q upon the operation of any key through the medium of the rear extension S of the bell-crank J, in the well-known manner.

The money-drawer or till T is pivotally supported by laterally-projecting studs c on links U, (preferably two on each side of the drawer,) pivoted on studs d, projecting inward from the sides of the compartment P. (In 85 the drawings, the rear side wall of the drawer-compartment not being shown on account of the sectional views, the studs d shown in said views appear in cross-section.) Secured to the upper rear side of the drawer T is the 90 usual locking-plate W, which engages the bolt Q to automatically lock the drawer when the latter is pushed into its compartment. It results from this construction and the pivotal arrangement of the drawer that whenever the bolt Q is lifted by the operation of 95 a key and the drawer thereby released the latter will by its own gravity be thrown outward and downward and partially propelled from the case; and, to enable it to be pulled 100

still further outward to give better access to its interior, I provide the upper ends of the links U with slots e, in which the supporting-studs c on the sides of the drawer have play, 5 so that when the drawer is released and thrown forward it can be pulled out to the position shown in Fig. 2. When it is desired to close the drawer, it is pushed inward and upward, the studs c slipping back to the 10 rear lower ends of the slots e, and the drawer then rising on the links U and becoming automatically locked in its closed position, as shown in Fig. 1. The front wall of the drawer is extended downward, as shown, to completely cover the opening in the front of the compartment when the drawer is in its closed 15 position.

I do not wish to be limited to any particular arrangement of the drawer T and supporting-links U, as that may be largely varied without departing from my invention or changing the mode of operation of the drawer. For instance, in Fig. 3 I have shown an arrangement of the drawer in which

it is suspended on the links U, the latter being pivoted in the upper part of the compartment instead of the lower. 25

Having thus fully described my invention, I claim—

1. In a cash register and indicator, the combination, with the operating-keys and a drawer-locking device actuated thereby, of the money-drawer or till T, supported on the pivoted links U, and arranged to operate substantially in the manner and for the purpose 35 specified.

2. In a cash register and indicator, the combination, with the operating-keys and a drawer-locking device actuated thereby, of the money-drawer or till T, supported on the 40 pivoted links U by slot-and-pin connections, and arranged to operate substantially in the manner and for the purpose specified.

JOHN H. PATTERSON.
